PATENT NO. : D889,772 S
APPLICATION NO. : 29/709836
DATED : July 14, 2020
INVENTOR(S) : Pamela Noel

Page 1 of 9

It is certified that error appears in the above-identified patent and that said Letters Patent is hereby corrected as shown below:

On the Title Page

The title page showing the illustrative figure should be deleted and substitute therefore the attached title page.

In the Drawings

Delete drawing sheets 1-7, consisting of Figs. 1-7, and substitute therefor the corrected drawing sheets 1-7, consisting of Figs. 1-7, as shown on the attached pages.

Signed and Sealed this
Twenty-second Day of June, 2021

Drew Hirshfeld
*Performing the Functions and Duties of the
Under Secretary of Commerce for Intellectual Property and
Director of the United States Patent and Trademark Office*
